BUILDING BRICK AND WALL

Benjamin Roman, New York, N. Y.

Application February 23, 1938, Serial No. 191,980

11 Claims.

(Cl. 72—45)

This invention relates to a building brick to be used for building exterior walls of a house, also to such a wall, and to wall insulation.

Heretofore, brick exterior building walls were erected by the usual method of bricklaying, and plastering with painting were resorted to for completing the interior of the wall. At present, however, those methods, which go back to times immemorial, are considered objectionable for several important reasons. Due to many social and economic conditions, there has arisen a vast requirement for low cost housing, low cost housing maintenance, and improved comforts. Thus, it is deemed essential that the initial cost of housing erection should be greatly reduced, that maintenance costs be likewise reduced, that house cares connected with heating be eliminated and such heating be obtainable at low cost, and that exterior walls be insulated against summer heat, as well as rendered fireproof. It is recognized that comfortable heating is acquirable by resorting to automatic systems, such as oil or gas firing controlled by thermostatic devices, and that due to the high cost of operating these systems it is also imperative that the exterior walls of the building be efficiently insulated. Such insulation can be economically provided for non-fireproof frame buildings, wherein the exterior walls are hollow and therefore afford intervening space which can be simply filled with highly efficient insulation, such as "mineral wool". For brick buildings, however, the latter method cannot be resorted to because its exterior walls are necessarily solid.

The principal object of the invention is to accomplish all of the above mentioned aims, and to provide a building brick wherewith an exterior building wall may be erected that will supply the aforesaid sought for advantages of low cost erection, elimination of interior wall maintenance and redecorations, improved insulation, and resulting reduced cost of automatic heating, wherein all other comforts incident thereto are attained.

Other objects and advantages will hereinafter appear.

In the accompanying drawing—

Fig. 1 is a perspective view, partly in cross-section and partly in full, showing a portion of a wall constituting the invention.

Fig. 2 is a plan view of the building brick constituting the invention.

Fig. 3 is a side elevation of the brick shown in Fig. 2.

Fig. 4 is a plan view showing a portion of an

exterior building wall which is a modification of the invention, and wherein there are utilized bricks of a modification of the invention.

Fig. 5 is an end elevation of one of the bricks shown in Fig. 4.

The brick 1 is made of substantially the same or similar materials as those utilized for the manufacture of ordinary bricks, and comprises a solid portion 2 which conforms to an ordinary building brick and a portion 3 which is integral therewith but hollow, providing a front face 4 and corner brackets 5 which join said face with the brick-portion 2, thereby forming windows 6 for the hollow space or chamber 7 of the portion 3. The chamber 7 is completely filled with an efficient insulating material 8, such as "mineral wool", and each of the windows 6 is covered over with a pane 9 consisting of wire cloth, which may be of the type utilized for window screens in summertime, by which means the insulating material 8 is securely and efficiently maintained in the requisite free fluffy condition required for it. The wire cloth panes 9 are retained in place by being either molded directly in the brick material or cemented thereto. In the rear part of the solid brick portion 2 is formed a recess 10 which serves for manipulation during the handling of the bricks or in the bricklaying, the operative inserting his fingers in the said opening while applying the thumb to the face 11 of the brick to thereby handle it conveniently. The thickness of hollow brick portion 3 is greater than that of the solid portion 2, as shown in Fig. 3, as in the building of the wall the top and bottom faces 12 of portions 3 of adjoining bricks 35 contact with each other, while the faces 13 of the solid portions 2 are separated by the intervening binding mortar 14, as clearly illustrated in Fig. 1. On its front face 4 the hollow brick portion 3 is provided with a surface 4a, which is 40 tiled or otherwise decoratively finished to render it suitable for the purposes required of a wall of the interior of a room, such treatment of said surface being indicated by the dash and dot lines, Fig. 2.

When building a wall 15, Fig. 1, with the bricks 1, the latter are laid in the ordinary manner, with the mortar 14 disposed between the faces 13 of its solid portions 2, and the process is continued until the entire wall is completed, the joints 4b of interior faces 4 being properly pointed up in the manner of an ordinary tile wall. As the wall 15 is thus finished, therefore, it constitutes an efficient solid brick wall 15a consisting of the solid portions 2 of the bricks 1, 55

while integral therewith there is simultaneously erected a hollow brick wall 15b carrying therewith a filler 8 of "mineral wool" insulation, which extends therethrough contiguously, vertically and laterally throughout the wall, except for the intervening wire screens 9 and the adjoining brick-brackets 5, that do not however materially effect the otherwise substantially uninterrupted insulation material 8.

According to the modification shown in Figs. 4, 5, a brick 16 is provided, which embodies all the elements of the portion 3 of brick 1, but is unconnected with any solid portion, this brick having a closed rear face 17. The above described wall 15 is of a bulk suitable for small or moderate-sized homes or dwellings, but for building larger houses a sufficiently thick wall 18 may be built with ordinary bricks 19 in the usual manner, and upon its interior side a wall consisting of the insulation bricks 16 may be erected as shown in Fig. 3, by the rear faces 17 being mortared, as shown at 20, to the brick wall 18. In this erection, the bricks 16 are laid in contact with each other without any mortaring, while their meeting joints may be pointed up in the manner of a tiled wall.

While a number of good insulation materials may be utilized for filling the chamber 1 of the brick, the particular material known as "mineral wool" is hereinabove specified because of its high reputation for insulating efficiency, and it will be noted that due to the construction of this brick and the enclosure of its chamber 1 by the wire cloth panes 9 the "mineral wool" will at all times be maintained therein in the free uncompacted fluffy condition which is requisite to this material and to its efficiency.

It will be evident that in erecting a dwelling with the outside walls of this invention, and utilizing the bricks of the invention, all of the advantages hereinabove referred to will be attained. By erecting the partitioning walls of the rooms with tile-facings corresponding to the surface 4a of the bricks, it will not be necessary to resort to lathing, plastering, kalsomining, and painting of the walls, which will result in greatly reducing the initial cost of the building. Also, subsequent repeated plaster repairs and redecoration expense will be eliminated, thereby reducing maintenance expenses. The fireproof character of these walls will likewise obviate losses and reduce insurance costs. The efficient insulation of these walls will keep the house warm in winter and cool in summer, and will greatly reduce the cost of automatic heating, as well as providing the well known comforts incident to such heating.

Variations may be resorted to within the scope of the invention, and portions of the improvements may be used without others.

Having thus described my invention, I claim:

1. A building brick comprising the combination of an exterior solid portion having dimensions and weight of a regular exterior wall brick, another interior portion integral with said portion intended to form the interior side of a wall, said latter portion being hollow and having windows on top, bottom, and sides thereof, and said hollow chamber and windows being filled with insulating material.

2. A building brick comprising the combination of an exterior solid portion having dimensions and weight of a regular exterior wall brick, another interior portion integral with said portion intended to form the interior side a wall,

said latter portion being hollow and having windows on top, bottom, and sides thereof, said hollow chamber and windows being filled with insulating material, and said windows being covered with wire cloth to retain said material. 5

3. A building brick comprising the combination of an exterior solid portion having dimensions and weight of a regular exterior wall brick, another interior portion integral with said portion intended to form the interior side of a wall, 10 said latter portion being hollow and having windows on top, bottom, and sides thereof, said hollow chamber and windows being filled with insulating material, and said windows being covered with means to retain said material. 15

4. A building brick comprising the combination of an exterior solid portion having dimensions and weight of a regular exterior wall brick, another interior portion integral with said portion intended to form the interior side of a wall, 20 said latter portion being hollow and having windows on top, bottom, and sides thereof, said hollow chamber and windows being filled with insulating material, and the face of said second portion being windowless and treated for interior 25 decoration.

5. A building brick comprising the combination of an exterior solid portion having dimensions and weight of a regular exterior wall brick, another interior portion integral with said portion intended to form the interior side of a wall, 30 said latter portion being hollow and having windows on top, bottom, and sides thereof, said hollow chamber and windows being filled with insulating material, said windows being covered 35 with means to retain said material, and the face of said second portion being windowless and treated for interior decoration.

6. A building brick for the interior side of a wall having dimensions and weight for manipulation with one hand, said brick being hollow and provided with windows on top, bottom, and sides thereof, said hollow chamber being filled with insulating material, and said windows being covered with wire cloth to retain said material. 40 45

7. A building brick for the interior side of a wall having dimensions and weight for manipulation with one hand, said brick being hollow and provided with windows on top, bottom, and sides thereof, said hollow chamber being filled 50 with insulating material, and said windows being covered with means to retain said material. 55

8. A building brick for the interior side of a wall having dimensions and weight for manipulation with one hand, said brick being hollow and provided with windows on top, bottom, and sides thereof, said hollow chamber being filled 60 with insulating material, said windows being covered with means to retain said material, and the interior face of said brick being treated for interior decoration.

9. A building brick comprising the combination of an exterior solid portion having dimensions and weight of a regular exterior wall brick, another interior portion integral with said portion intended to form the interior side of a wall, 65 said latter portion being hollow and having windows on top, bottom, and sides thereof, said hollow chamber and windows being filled with insulating material, and said hollow portion being thicker than said solid portion for interposition 70 of mortar for said solid portion.

10. A building brick comprising the combination of an exterior solid portion having dimensions and weight of a regular exterior wall brick, 75

another interior portion integral with said portion intended to form the interior side of a wall, said latter portion being hollow and having windows on top, bottom, and sides thereof, said hollow chamber and windows being filled with insulating material, and said solid portion having a recess for inserting fingers for grasping the brick.

5 11. A building brick comprising the combination of an exterior solid portion having dimensions and weight of a regular exterior wall brick,

another interior portion integral with said portion intended to form the interior side of a wall, said latter portion being hollow and having windows on top, bottom, and sides thereof, said hollow chamber and windows being filled with insulating material, said hollow portion being thicker than said solid portion for interposition of mortar for said solid portion, and said solid portion having a recess for inserting fingers for grasping the brick.
